US00D736213S

(12) **United States Design Patent**
Kang et al.

(10) **Patent No.:** US D736,213 S
(45) **Date of Patent:** ** Aug. 11, 2015

(54) **MEMORY CARD**

(71) Applicant: **SAMSUNG ELECTRONICS CO., LTD.**, Suwon-si (KR)

(72) Inventors: **Il-Mok Kang**, Suwon-si (KR); **Ki-Woong Yoo**, Jeonju-Si (KR); **Gwang-Man Lim**, Seoul (KR); **In-Jae Lee**, Whaseong-si (KR); **Seok-Jae Han**, Seoul (KR)

(73) Assignee: **SAMSUNG ELECTRONICS CO., LTD.**, Suwon-si (KR)

(**) Term: **14 Years**

(21) Appl. No.: **29/513,288**

(22) Filed: **Dec. 30, 2014**

(30) **Foreign Application Priority Data**

Jul. 1, 2014 (KR) 30-2014-0032274
